PORTRABLE TOILET HOUSING UNIT

James M. Kulka, 1623 S. Jefferson St., Chicago, Ill.

Filed Sept. 22, 1961, Ser. No. 66,803

Term of patent 14 years

(Cl. D13—1)

I claim:

The ornamental design for a portable toilet housing unit, substantially as shown.
